UNITED STATES PATENT OFFICE

92,185

DESIGN FOR A TOILET ACCESSORY CONTAINER

Joseph S. Lindemann, New York, N. Y.

Application December 27, 1933, Serial No. 50,222

Term of patent 14 years

To all whom it may concern:

Be it known that I, JOSEPH S. LINDEMANN, a citizen of the United States of America, residing at New York city, county of New York, Borough of Manhattan and State of New York, have invented a new, original, and ornamental Design for a Toilet Accessory Container, of which the following is a specification, reference being had to the accompanying drawing, forming a part thereof:

I claim:

The ornamental design for a toilet accessory container as shown.

JOSEPH S. LINDEMANN.
